BALLOON AND METHOD OF PRODUCING
SAME

James F. Boyle, Teaneck, N. J.

Application February 24, 1936, Serial No. 65,195

2 Claims. (Cl. 244—33)

This invention relates generally to lighter-than-air craft and is more especially directed to improvements in the methods of producing and using balloons and similar inflatable devices, for various purposes and particularly as may be employed for so-called aerial advertising and aerial displays.

As is well known, signs and other advertising material has been carried aloft by balloons of the conventional one cell or single gas bag types of spherical and elongated designs, inflated with helium or hydrogen gas. Also, for certain purposes, the balloons have taken the form of grotesque or other figures, as characters in children's stories, the balloons of these latter types being held captive by hand lines to float above those holding the lines who may be participants in a procession or street parade. However, in every instance, heretofore, the balloons, in whatever form they may have appeared, have been produced in the unit cell designs and, consequently, their use has been restricted because of their cost and the limitations that are imposed in their use by inflation, transportation and handling requirements. Obviously, to contain the requisite cubic feet of gas, the envelopes and the gas containers must be of relatively large dimensions, rendering them unwieldy when collapsed and calling for special inflation equipment, in addition to providing suitable areas for their preparation for performance. While the advantages of so-called balloon advertising are recognized, the difficulties and expense which flow from the use of balloons of a construction conforming to standard practice have substantially prevented the development of this form of publicity or display.

Therefore, the general object of this invention is to promote the development of aerial advertising and the use of aerial display devices, by providing a simple and economical method and means, whereby the requisite flotation media may be produced, handled and operated with a maximum of efficiency at a minimum of cost for the results that may be attained from services of the kind.

More specifically, it is an important object of this invention to improve and simplify the construction of balloons as used in the navigation of the air and for observation and other customary purposes, as well as for use as sustaining media for advertising and other material and in functioning in aerial displays.

It is a further object of my invention to reduce the cost of production and maintenance of

balloons generally, and particularly those intended for use in connection with aerial advertising and displays, by eliminating the single and relatively expensive gas container, as in standard constructions, and obviating those difficulties which are a concomitant of their use.

Another object of this invention is to provide a balloon that is especially adapted to the requirements of aerial advertising and display services, which may be collapsed for transportation or inflated and sent aloft in appreciably less time than similar operations may be performed in the single gas container types, the characteristics of my invention being such as to facilitate repairs and replacements with a minimum loss of service and small material and labor expense.

Also, it is a further important objective of my invention to provide a simplified method of constructing a balloon to take a form other than that of the conventional spherical and elongated or substantially cigar-shaped types, as in producing replicas of figures of animals, birds, persons and the like, for display, amusement and other purposes, whereby such devices may be more extensively used and will operate efficiently under atmospheric conditions which would render the functioning of such devices, as heretofore produced, unsatisfactory.

Other objects and advantages flowing from the practicing of my invention will become manifest as the description proceeds, and I would have it understood that I reserve unto myself all rights to the full range of equivalents, both in structure and in use, to which I may be entitled, under my invention, in its broadest aspect.

For the purposes of this disclosure, I have elected to illustrate and describe my invention as it may be practiced in aerial advertising and aerial display services. It will be evident, however, that my invention is capable of numerous other applications in the balloon art, and that this election is merely illustrative and is not to be construed, in any sense, as a limitation of my invention beyond the scope of the appended claims.

In the drawings:

Figure 1 is a view in elevation of a balloon, constructed in accordance with my invention, the envelope being of the conventional approximately spherical form.

Figure 2 is a cross-section on the line 2—2 of Figure 1.

Figure 3 is a view illustrating a method of aerial advertising, a sign being supported by

tween two balloons conforming to my invention.

Figure 4 is a view in elevation of a balloon embodying my invention, produced in the figure of a dog.

Figure 5 is a longitudinal section of the balloon shown in the preceding figure, and

Figure 6 is a transverse vertical section on the line 6-6 of Figure 5.

Referring now to the drawings in detail, in which like characters of reference are employed to designate similar parts in the several views, and more especially to the device of Figures 1 to 3, inclusive, 7 indicates the envelope or outer covering of the balloon which may be of cord or rope net, as shown or other suitable water-proofed or non-waterproof material of the weight and strength requisite for the work which it is to perform.

The envelope 7 is peripherally conformed to provide, in effect, a bag of the conventional spherical shape when distended, as hereinafter described, the open end being defined by the depending portions 7a, which may be integral with the body or sewn or cemented thereto, to which is affixed, by knotting or otherwise, one end of a guy rope 8, the other end of such rope being secured to the ring or loop 9, which forms a connector common to all of said ropes and provides a means to which the anchoring or main

rope 10 may be secured.

Hydrogen, helium or other gas may be used to render the balloon buoyant in the air, as in existing types. Carbon-dioxide, which is commercially available in various capacity containers lends itself especially to the practicing of the present invention, because of its relatively low cost, ease in transporting and handling and the fact that in lieu of a single gas cell or bag, I employ a plurality of small cooperating containers to impart the necessary buoyancy to the balloon in performing its intended function. These gas cells may be of any suitable configuration, as spherical, elongated or cylindrical or the like. In the present showing they are spherical so-called balloonettes, indicated at 11. Each cell embodies means, as a valve controlled inlet 12, for individual inflation and deflation, in any appropriate manner.

When it is desired to employ the balloon for advertising purposes, the aforesaid envelope, whether of net or other material, which is substantially circular in outline, is spread upon a flat surface and the cells inflated individually, in proximity to the envelope or at a point remote therefrom. As each cell is charged and sealed, it is inserted within the envelope, the mouth of the latter being gradually constricted as gas-containing spheres are added, until the last one is confined therewith, when the envelope will assume approximately the peripheral contour shown in Figure 1, the balloonettes being retained in close cooperating association therein, as will be clearly evident from Figure 2 of the drawings. In locating the gas containers within the envelope, they are preferably arranged in superposed groups, the group in the central zone containing the greatest number of containers, while the number of containers in each of the remaining groups progressively decrease toward the top and bottom sections of the envelope. Of course, this particular placement of the cells or balloonettes may be deviated from as may be desired or required, to obtain any other requisite peripheral contour in the envelope or covering, whether a net or otherwise.

The balloon is now ready to be sent aloft and the anchor rope 10, to which the advertising banner may have been previously attached, is paid out until the balloon reaches a predetermined altitude. Two balloons, with the banner therebetween, as indicated at 13, in Figure 3, may be employed or otherwise.

While the gas cells or containers 11 are normally independent and may be inflated or deflated individually, it will be noted that each furnishes its proportion of the lift necessary to perform a given amount of work, the shape of the confined cells providing for the normal expansion thereof within the envelope, in response to atmospheric variations.

In the embodiment of the invention shown in Figures 4, 5 and 6, the envelope 7 is composed of fabric, preferably waterproofed, which is cut into appropriate patterns and assembled by stitching or cementing to produce the representation of the figure of a dog, when distended, the head 7a, neck, 7b, legs 7c and tail 7d, preferably communicating with the body or main section 7e of the envelope. Similarly, to the structure of the preceding figures, the replica of the dog is expanded to the desired degree, by the use of independent gas containers or cells of spherical or elongated shapes, each, of course, being inflatable and deflatable independently of its associated cells.

Because of the different shapes and dimensions of the several components of the figure of the dog, it is obvious that it will be desirable to likewise employ containers of different sizes and of different shapes in association. For example, in the main or body section, three large balloonettes 14, 14a and 14b may be used, while in each of the legs the balloonettes are of smaller sizes and gas capacities, as shown at 15, 15a and 15b. The same is true as to the cells employed in the formation of the head and nose, while a single cell 16 serves for the formation of the neck. The ears 7f may be composed solely of the envelope material, or they may each have an appropriately shaped cell disposed therein, which is just barely distended to maintain the requisite flat appearance of the ears in front elevation. The tail 7d, is distended by a specially shaped balloonette 17, the gas being introduced to the balloonette through the tube or neck portion 7a thereof. Similar means for inflating and deflating each of the balloonettes entering into the composition of the figure are shown at 14', 15', 16' and 18'. These neck or tubular portions of the cells, just referred to, may protrude through openings in the envelope 7, or they may be concealed therewith. To the latter end, the envelope may be slit, as at 19, at appropriate points to provide for the entry of the balloonettes therein in partially inflated condition this slit having an associated flap, stitched or cemented in juxtaposition thereto, which is adapted to be drawn over the slit in superposed relation to the inner wall, it being obvious that it will be retained in place by the pressure of the cell thereagainst, when the latter is in functioning condition. In lieu of such flaps, indicated at 20, other closures may be utilized, or as previously pointed out all forms of closures may be omitted.

In the employment of this form of my invention, the body section is preferably first distended, by inserting partially inflated cells therein, in the association shown, through the aforesaid openings or slits 19, and then proceeding in like manner with the preliminary dilation of the head and other members of the figure. Follow-

ing this preliminary inflation, complete inflation of the cells may be effected and the inflating necks properly stowed within the envelope in the manner heretofore described. Of course, the inflation operation may be otherwise performed to suit the requirements of the operators, the sequence of the steps being variable.

As in the construction of Figures 1 to 3, inclusive the figure is preferably provided with tabs or other media sewed or cemented thereto, indicated at 1aa, to which guy or hand ropes may be attached for carrying the figure if inflated with a gas to give it a negative lift or for holding it down if it possesses a positive lift. Likewise, as will be evident, the envelope 7 in either case may be variously colored, the treatment of the envelope to render it waterproof or water repellent, as heretofore pointed out, eliminating the hazard of the envelope material absorbing moisture and becoming too heavy for the gas cells to function in the prescribed manner.

From the foregoing, it will be perceived that where a balloonette becomes defective, from any cause, it may be readily replaced and the balloon restored to service with a minimum amount of labor and little loss of time, whereas with a balloon of the conventional type, if the single cell develops leakage, the balloon must remain out of service for a considerable time and the labor involved adds to the loss suffered by the user. In addition to this, the entire charge of gas, whether it is hydrogen or helium, is lost, with the attendant expense of recharging, while the inflation of a balloonette, in replacing a defective or damaged one, is relatively infinitesimal. Another advantage of the balloonettes resides in preserving the envelope against rupture, in the expansion of the contained gas in response to the heat of the sun or because of altitude. With the air spaces between the associated cells or balloonettes, there is ample room for their expansion, without communicating any strain to the envelope, the resulting distortion of the containers from their normally functioning shapes having no effect upon the external appearance of the balloon or figure, as the case may be.

It will be manifest that a predetermined number of balloonettes, having a known capacity of cubic feet of gas will provide the buoyancy necessary to sustain a fixed maximum load. Hence, the effective buoyancy of the balloon may be varied, within such limits as may be essential to meet the requirements of economical operation, under various basic conditions. This, of course,

applies to the use of my invention in any of its multiplicity of applications, as heretofore outlined or specifically pointed out.

Where a reticulated fabric is used, the mesh, of course, must be of a size to insure the retention of the balloonettes within their covering in operation. However, in actual practice of my invention, commercially, I have found that it is preferable to have the cells independently inflatable and deflatable. Likewise, this practical use has demonstrated the simplicity in handling, low production and maintenance costs and the practicability of employing carbon-dioxide gas as the inflating element to obtain efficient results from the standpoint of both the manufacturer and the user, all of these being objectives to which my invention is directed, as hereinbefore set forth.

I claim:

1. A balloon having an envelope formed with a large body portion and relatively smaller portions of varying sizes and contours, cooperating with said body portion to produce a figure of a preconceived design, a plurality of individual gas cells inflatable to different sizes independently insertable within the cooperating portions of said envelope, each cell embodying a neck adapted to protrude from said envelope for inflating said cells when located therein, in a predetermined relationship to each other and to the portions of the envelope in which they are to function, means integral with said envelope for concealing the necks of said cells when inflated to impart to said envelope an uninterrupted external surface and means associated with said envelope to which media may be attached for holding the balloon captive or for transporting it.

2. A balloon adapted to take a preconceived form in representation of an animal or the like including an envelope embodying portions formed to simulate corresponding parts of the animal to be represented, a plurality of individually inflatable gas cells of different sizes independently insertable within said envelope portions, each cell including an extension shaped to protrude from said envelope for inflating said cells when positioned therein in a predetermined relationship to each other and to the parts of the envelope with which they are associated, means for concealing said extensions within said envelope to impart to the latter an uninterrupted external surface and carrying devices fixed to said envelope.

JAMES F. BOYLE.
